UNITED STATES PATENT OFFICE.

JOHN S. BARKER, OF ROCHESTER, NEW YORK.

MECHANICAL TIME FUSE.

Application filed October 18, 1921. Serial No. 508,556.

(GRANTED UNDER THE ACT OF MARCH 3, 1883; 22 STAT. L. 625.)

To all whom it may concern:

Be it known that I, JOHN S. BARKER, a citizen of the United States, and a resident of Rochester, county of Monroe, and State of

5 New York, have invented an Improvement in Mechanical Time Fuses, of which the following is a specification.

The invention described herein may be used by the Government or any of its officers or employees in prosecution of work for the Government, or by any other person in the United States without payment to me of any royalty thereon in accordance with the act of March 3, 1883.

15 The subject of this invention is a mechanical time fuse and the invention relates more particularly to the firing mechanism therefor.

Mechanical time fuses, as generally constructed are provided with a chronometric motor or watch works mechanism attached to the fuse body, the motor or mechanism adapted to rotate an arm which, normally, is attached to or engaged by the timing or setting ring but which, when acted on by the forces set up upon the firing of a projectile carrying the fuse from a gun is released from its connection or engagement with the ring and attached to the main shaft of the motor to rotate therewith. The purpose of this arm is to trip the firing mechanism at a predetermined time.

20 My invention is designed to provide such a fuse with an arm which is permanently connected to the driving shaft and which has no connection or engagement with the timing or setting ring.

25 The invention also contemplates the provision of a firing mechanism carried by the timing ring and movable therewith.

30 A still further object contemplated by the invention is a novel means for connecting the motor to the fuse body.

35 The invention also contemplates the provision of means for imparting the wave of detonation to the magazine or booster charge in all positions of the timing ring.

40 With the foregoing and other objects in view which will appear as the description proceeds, my invention consists in the novel arrangement and combination of parts and in the details of construction hereinafter described and claimed, it being understood that changes in the precise embodiment of

the invention herein disclosed may be made 55 within the scope of what is claimed without departing from the spirit of the invention.

One practical embodiment of the invention is illustrated in the accompanying drawings, wherein:

Fig. 1 is a sectional view of a fuse constructed in accordance with the invention, the end partly broken away;

Fig. 2 is a plan view of the same; 65

Fig. 3 is a view in elevation of the complete fuse;

Referring to the drawings by characters of reference:

I provide a fuse body A formed with the 70 usual threads A' by which the fuse is screwed into the opening in the forward end of the shell or projectile.

A cavity is provided in the body A forming a magazine for the reception of powder 75 A² which is held in place in the cavity by a screw plug as shown or in any other suitable manner. The form of fuse body herein shown is for use with shrapnel shells, it being understood that the charge of powder A² may be replaced by the usual detonator and booster charge for use in high explosive shells. The magazine is in communication through a series of ducts one of which is shown at A⁴, with an annular 80 groove A³ formed in the body A and adapted to be filled with powder as shown, or other explosive.

The usual timing ring B is provided, which seats upon the body A and there is 90 interposed between the body and ring an annular washer C of felt or similar material which is shellacked or otherwise cemented to the body A.

For the purpose of securing the ring to 95 the body I prefer to provide apertures in the body A for the reception of screws G and G' which are threaded into tapped recesses in the lower plate of the motor casing. The ring is formed with an annular shoulder 100 upon which the motor casing rests thus holding the ring in place upon the body.

The timing ring B is formed with a partly cut-away portion between the lines B' and B² and has an aperture communicating with 105 this cut-away portion for the reception of a detonating or fulminating cap B¹ and the firing end of the firing pin B³, the other

end of which is positioned with a close sliding fit in an opening formed in a bridge piece D which bridges the cut-away portion.

A coiled spring B⁴ encircles the stem of the firing pin B³, being confined between the bridge piece D and a collar formed on the pin, and the pin is normally retained in unarmed position by a supporting roller B⁵ which is formed with a cut-away portion in which the collar rests; the spring B⁴ exerting pressure on the roller through the collar to one side of the longitudinal axis of the roller, thus tending to rock the roller and free the collar.

15 To prevent the roller from rocking, a lever or crank arm B⁶ is rigidly affixed thereto and the free end of this arm is normally positioned in a slot D' formed in the bridge piece D. The lever is retained in position 20 in the slot by a latch block D² pivoted to the bridge piece by a pin D³ and having secured thereto a pin D⁴ through which the latch is rocked to release the lever, as will be herein-after described. The block D² is held from 25 accidental displacement clock-wise by a shoulder formed on the bridge piece D against which it rests and, in the other direction by a centrifugal weight pivotally mounted on the pin D⁶ and held normally by 30 spring D'.

An arm E is secured to the main shaft of the motor to rotate therewith and upon this arm is carried an arm E' which has a limited sliding movement longitudinally thereof and 35 is normally held in retracted position by a spring E². The arm E' is so proportioned that when the ring is turned in setting the fuse the pin D⁴ of the latch D² will pass the arm without contact therewith, but when the 40 device is rotated as when a shell is in flight centrifugal force acting on the arm E' will overcome the effect of the spring E² thus bringing the arm E' to its extended position, in which instance the pin D⁴ will lie in the 45 path of travel of the arm.

From the foregoing it will be seen that for any setting of the ring B the fulminate cap B⁷ will always be in operative position with 50 respect to the groove A³ and, because of the connection of the groove through the ducts A⁴ with the magazine A², instantaneous explosion of the magazine charge is assured.

The position of the zero point B⁸ in the 55 graduations on ring B has a definite relation to the position of the firing pin mechanism and the position of the setting mark A⁶ on the body has a definite relation to the position of the arm E'. To set the fuse for any 60 desired time it is only necessary to change the position of the firing pin mechanism with relation to the arm E', the maximum setting requiring a movement of the arm through slightly less than 360°. Setting is performed 65 by turning the ring B together with the cap F with relation to the body A, the coinci-

dence of the graduations with the setting mark A⁶ denoting the desired time of flight or range of the projectile to the point of burst. In setting, the pin D⁴ is permitted to pass the arm E', the arm being in its retracted position as shown in the drawing. In the flight the arm E' is held by centrifugal force in its extended position so that in its movement it comes in contact with the pin D⁴. The centrifugal lock D⁵ in flight 75 swings outward to a position which releases the lock D² which is then held only by friction due to pressure of B⁶ until moved by the arm E' contacting the pin D⁴.

What I claim is:

1. In a mechanical time fuse, including a fuse body; provided with an explosive chamber, an annular groove and ducts connecting the chamber and groove; a timing ring mounted on the body and movable with respect thereto, a primer carried by the ring in position to flash into the groove when exploded and describing an arc concentric with the groove when the ring is rotated, a firing pin carried by the ring for firing the primer, a block mounted for rocking movement on the ring, said block having a cut-away portion, a collar on the pin and normally resting in the cut-away portion of the block, to retain the pin in unarmed position, a latch for normally holding the block against rocking movement, a centrifugal catch normally holding the latch, a motor connected to the fuse body and an arm moved by the motor and normally passing the latch without contact therewith and moved by centrifugal force to a position to contact the latch to free the block and permit the pin to fire the primer.

2. A mechanical time fuse, including a fuse body; provided with an explosive chamber, an annular groove and ducts connecting the chamber and groove; a timing ring mounted on the body and movable with respect thereto, a primer carried by the ring in position to flash into the groove for all settings of the ring, a firing pin carried by the ring for firing the primer, a block mounted for rocking movement on the ring, said block having a cut-away portion, a collar on the pin and normally resting in the cut-away portion of the block to retain the pin in unarmed position, means for normally holding the block against rocking movement, a motor connected to the fuse body and an arm carried by the motor and normally movable past the block holding means without contact therewith and acted upon by centrifugal force to move to a position to contact said means and trip the same to release the block.

3. A mechanical time fuse, including a fuse body, provided with an explosive chamber, an annular groove and ducts connecting the groove and chamber, a timing ring

mounted on the body and movable with respect thereto, a primer carried by the ring in position to flash into the groove for all settings of the ring, a firing pin carried by the ring for firing the primer, means for normally holding the firing pin in unarmed position, a motor connected to the fuse body and an arm carried by the motor connected to the fuse body and an arm carried by the motor normally movable past the pin holding means without contact therewith and moved by centrifugal force to a position to contact the holding means.

4. A mechanical time fuse, including a fuse body, an explosive in the body, a timing ring mounted on the body and movable with respect thereto, a primer carried by the ring for igniting the explosive, a firing pin mounted on the ring for firing the primer, means for normally holding the firing pin in unarmed position, a motor connected to the fuse body and means moved by the motor to trip the pin holding means to release the pin, said means normally movable past the holding means without contact therewith and moved by centrifugal force to a position to contact the same.

5. A mechanical time fuse, including a fuse body, a timing ring mounted on the body, a firing mechanism carried by the ring and movable therewith and means connected to the body for releasing the firing mechanism, said means normally movable past the firing mechanism without contact therewith and moved by centrifugal force to a position to contact the same.

6. A mechanical time fuse, including a fuse body, a timing ring mounted on the fuse body, firing mechanism carried by the timing ring and movable therewith, said mechanism normally held in unarmed position, and means carried by the fuse body for tripping the firing mechanism, said means movable past the firing mechanism without contact therewith during setting of the fuse.

7. A mechanical time fuse, including a fuse body, a timing ring mounted on the fuse body, firing mechanism mounted in the fuse, and means for tripping the firing mechanism, said means adapted to pass the firing mechanism during setting of the fuse without contact therewith.

8. A mechanical time fuse, embodying a fuse body, a timing ring mounted on said body and movable with respect thereto, firing means carried by the ring and movable therewith and an arm for tripping the firing means connected to the fuse body and normally stationary with respect thereto.

9. A mechanical time fuse, embodying a fuse body, a timing ring connected to the fuse body, firing means carried by the ring and movable therewith and an arm for tripping the firing means connected to the body.

10. A mechanical time fuse, embodying a fuse body, firing mechanism carried by the body and movable to predetermined positions to set the fuse and an arm for tripping the firing mechanism held stationary during setting of the fuse.

11. A mechanical time fuse, including a fuse body, a timing ring mounted on the body, firing mechanism mounted in the fuse, means for tripping the firing mechanism and an indicator on the body, having a fixed relation with respect to the tripping means and graduations on the ring, the zero of said graduations having a fixed relation with respect to the firing mechanism.

12. A mechanical time fuse, including a fuse body provided with an explosive chamber, an annular groove, and ducts connecting the chamber and groove, a timing ring mounted on the fuse body, a primer carried by the timing ring and in position to flash into the groove for all settings of the ring, and means for firing the primer.

13. A mechanical time fuse including a fuse body, a timing ring mounted on the body, a primer carried by the ring in operative position for all settings of the ring and means for firing the primer.

14. A mechanical time fuse, embodying firing mechanism and an arm for tripping the firing mechanism, the firing mechanism movable with respect to the arm to set the fuse.

15. A mechanical time fuse, embodying firing mechanism, an arm for tripping the firing mechanism and means for moving said arm, said means connected to the arm to secure unitary angular movement of the means and arm.

JOHN S. BARKER.
